Hughes Wassell, Chelmsford, England, as-
signors to Radio Corporation of America, a cor-
poration of Delaware

Application July 21, 1932, Serial No. 623,750
In Great Britain August 18, 1931

5 Claims. (Cl. 250—17)

This invention relates to radio and other high frequency circuit arrangements and is for improvements in or modifications of the invention disclosed in U. S. application Ser. No. 520,587, filed May 6, 1931, and in U. S. Patent #1,938,631, which resulted from said aforesaid application issuing on December 12th, 1933.

According to the invention contained in the said United States application Serial No. 520,587, 10 so-called absorber keying is effected in a radio or other high frequency circuit arrangement of the so-called absorber type by keying means arranged to alter the circuit conditions of a valve in such manner that said valve is connected in 15 circuit as an absorber valve during "spacing" but acts as an amplifier valve during "marking".

In the present specification the term "absorber modulating arrangements" is employed to refer to an arrangement of the kind in which a transmitter, which is modulated, is kept under load during "spacing" periods by means of one or more thermionic valves which are arranged to provide a load upon the source of anode potential when the transmitter is "spacing".

The present invention provides an improvement 25 in the invention disclosed in said United States application Serial No. 520,587, and the modified or improved arrangement is adapted for telephony, as well as for telegraph.

When a transmitter is employed, for example, 30 in duplex telephony, it is often desirable to suppress the transmitted carrier during intervals in speech so as to avoid setting up parasitic noises in the receiver. The present invention is particularly adapted for application to duplex telephone systems for this purpose though the said invention is not, of course, limited to this particular application for this particular purpose.

According to this invention carrier transmission is substantially suppressed during spacing, e. g. during intervals in speech, like in a modulated radio or other high frequency transmitter, said suppression of carrier being effected automatically by means operated in dependence upon the modulation input, the modulating arrangement being such that during the said suppression periods there is utilized as an absorber valve a valve which is utilized as an amplifier valve during other periods.

The invention is illustrated in Figs. 1 and 2 of the drawing accompanying this specification, which drawing shows the final magnifier stage of a transmitter in accordance with the present invention. In the drawing of the specification, parts corresponding to parts illustrated in the

drawing accompanying United States application Serial No. 520,587 are indicated with the same reference numerals as in the said drawing of United States application Serial No. 520,587. The earlier stages of the transmitter, of which the final stage is shown in the drawing of the present application, may be as illustrated in the drawing accompanying the specification of United States application Serial No. 520,587.

Referring to Figure 1 of the drawing, the final amplifier valve V_3 of a transmitter, whose self capacity may be neutralized as shown, may be coupled to the preceding stage 10 by means of a coupling condenser k_3 and receives anode potential from a source 12. The stage 10 may be an amplifier of high frequency oscillations and may include a source of high frequency oscillations. The grid circuit of the valve V_3 includes the grid electrode, the impedance Z_1 , the anode to cathode impedance of valve MV and the impedance between the grid and anode tied together and the cathode of GL in parallel as shown and extends to a tapping point P_3 upon a resistance Z . The circuit is completed by connecting the resistance Z to the cathode of V_3 . The tapping point P_3 and resistance Z correspond to the similarly marked tapping point and resistance in the arrangement illustrated in the drawing accompanying United States application Serial No. 520,587.

The impedances of the valves MV and GL are reversed as shown. The purpose of the valve GL is primarily to permit the negative potential set up across the resistance Z described more in detail hereinafter to be applied to the grid of the valve V_3 by way of tap P_3 on Z . This negative potential is required during spacing periods or periods between voice frequency modulations in order to set the valve V_3 at such a point on its characteristic that it will take the required dead loss feed and thus act as an absorber valve. Obviously the said negative potential cannot reach the grid of valve V_3 through the anode to cathode impedance of the modulating valve MV because the said valve is connected the wrong way. The required negative potential might, of course, be supplied by way of a high resistance shunting MV , but in this case the resistance would have to be extremely high or it would disturb the modulating characteristic of MV and might cause distortion. Moreover, in the presence of secondary emission from the grid of the valve V_3 during spacing conditions, a positive potential might arise on the grid of V_3 sufficiently high to overcome the negative potential supplied by the resistance Z and thus cause excessive current to

flow in the anode circuit of V_3 . The use of the one-way rectifier or valve GL overcomes the disadvantages which would arise from the use of a resistance at this point. The valve GL serves the same purpose as a high resistance leak across the modulating valve MV without introducing the danger mentioned above.

The tube MV permits the impedance of the grid circuit of tube V_3 to be varied at signal frequency. As shown, the impedance between the cathode and anode of MV is connected in series in the grid circuit of V_3 in a direction to permit the electron stream to flow from the cathode to the grid of V_3 and the current to flow in the opposite direction. An inductive impedance Z_1 and blocking condenser Bk_3 may also be included in the grid circuit of the valve V_3 . The resistance Z may be shunted as shown by a loop circuit comprising the anode to cathode impedance of a valve K' and a source of anode potential B' in series. Modulating potentials may be applied to the input electrodes of the valve MV from, for example, the secondary of a microphone transformer MT , whose primary may be energized from a microphone M as shown. The microphone M may also apply potentials to the input terminals of a speech amplifier and rectifier ATD . The rectifier ATD may also include a so-called "hang over" or delay circuit consisting of resistance and capacity in known arrangement to provide or produce a predetermined time constant. The output of the device ATD may be applied between the grid and the cathode of the valve K_1 , which valve may, if desired, be replaced by a plurality of valves in parallel. The grid and anode of the valve GL are connected together as shown and the said valve is so arranged as in effect to constitute a rectifying diode allowing negative potential to reach the grid of the valve V_3 but yet maintaining a high resistance in the reverse direction.

The action of the whole arrangement is as follows:

While speech is taking place rectified speech potentials are impressed on the grid of the valve K_1 via the time constant device ATD , these rectified potentials being of such value and the setting of the valve K_1 being such that the application of the said rectified potentials results in biasing the valve K_1 to "cut-off" and thereby preventing the source of potential B' from sending current through the resistance Z . The grids of the various stages in the transmitter including the stage V_3 shown are therefore connected to earth through their respective tappings on the resistance Z . The potential on the grids are such that oscillations are developed in the preceding stages, and amplified and modulated at speech frequencies in the stage V_3 and the transmitter accordingly functions in the normal manner. On cessation of speech, however, the rectified voltage applied to the grid of the valve K_1 will die away at a rate depending upon the time constant of the "hang over" circuit incorporated in the time constant device ATD . This time constant should be so chosen that the voltage on the grid of the valve K_1 is maintained during the intervals between words and phrases but ceases when an appreciable pause occurs.

When the rectified voltage is removed from the grid of valve K_1 said valve becomes conductive, a current flow occurs through the resistance Z due to the battery or other source B' , and the various stages in the amplifier will be either biased by potentials supplied to said stages from

the leads connected to points P_0 and P_2 on resistance Z , to "cut-off" and draw no current or set to draw "dead loss" anode current thereby acting as absorber valves in a manner similar to that described in United States application Serial No. 520,587 to maintain the load on the main source constant to the desired degree to improve regulation.

The signal modulated energy appearing in tank circuit 20 may be utilized in any known manner. It may be transferred to an antenna for radiation, to a load circuit, or to transmission lines.

The drawing illustrates in Figure 2 an arrangement wherein the present invention is applied to telegraphy.

The arrangement may be regarded as a modification of the arrangement shown in Figure 1, only such parts being shown in Figure 2 as are necessary to illustrate the nature of the modification.

Referring to Fig. 2, the arrangement of Fig. 1 is modified by substituting for the microphone M , microphone transformer MT , and associated amplifier and rectifier and time control device ATD , a keying relay or equivalent device M' , a resistance R , and a battery or other suitable source of potential B'' . The action of the arrangement in Fig. 2 is similar to the arrangement illustrated in Fig. 1 of the drawing so far as the suppression of the carrier is concerned, and, as will be appreciated, the operative difference is that the required negative biasing potential on the valve K' is obtained, not from speech voltages, but from the source of potential B'' . R is a limiting resistance of high value. The arrangement illustrated in the accompanying drawing results in a reduction of "key clicks"—an important improvement more particularly where duplex and two-way telegraphy is in question—and also presents the advantage that a high speed of telegraphy is possible since the keying contacts only have to handle minute currents and therefore the said key may be constituted by a high speed relay.

Having thus described our invention and the operation thereof, what we claim is:

1. A modulation system of the type in which oscillations are produced and applied to a thermionic repeater valve in which they are modulated and in which the repeater is rendered inoperative when no modulating potentials are impressed thereon, and in which preceding stages of the transmitter system are biased to draw current when said repeater is inoperative to thereby regulate the load applied to a common source of potential including a thermionic valve having its anode to cathode impedance connected in series with the cathode to control grid impedance of said repeater by way of a potentiometer, a device which is conductive in one direction only connected in parallel with the anode to cathode impedance of said thermionic valve, a rectifying device having its output electrodes connected by way of a source of potential in parallel to said potentiometer, and a source of modulating potentials connected to the input electrodes of said rectifying device and to the control grid and cathode of said thermionic valve.

2. A system as recited in claim 1 in which said device, which is conductive in one direction only, comprises the internal impedance of a thermionic valve which permits negative potential to flow from said source connected with said potentiometer to the control grid of said repeater, and in which a time constant device is interposed

between said source of modulating potentials and the input electrodes of said rectifying device.

5 3. A device as recited in claim 1 in which a time control device is interposed between said source of modulating potentials and the input electrodes of said rectifying device, and in which said potentiometer is tapped at appropriate points to provide biasing potentials for the control grids of valves in the transmitter preceding

10 the repeater valve recited.

15 4. A modulating system of the type in which oscillations are produced and applied to a thermionic repeater in which they are modulated and in which the repeater is rendered inoperative when no modulating potentials are impressed thereon including, a thermionic valve having its anode to cathode impedance connected in series with the cathode to control grid impedance of said repeater by way of a portion 20 of the resistance of a potentiometer, a thermionic discharge device which is conductive in one direction only connected in parallel with the anode to cathode impedance of said thermionic valve, a second thermionic device having its output electrodes connected in parallel to the 25 resistance of said potentiometer, and a source of modulating potentials connected to the input electrodes of said last named thermionic device

and to the control grid and cathode of said thermionic valve.

5 5. In a signalling system, a thermionic repeater of high frequency oscillations having a control grid and a cathode connected in a circuit to be energized by said oscillations, a first thermionic valve having a control electrode and having its internal impedance, in series with a source of direct current potential connected between the control grid and cathode of said repeater for normally biasing said repeater to a point at which no current flows therein, a source of modulating potentials, a second thermionic valve having a control electrode, a circuit including the impedance of said second thermionic 10 valve connected between the grid and cathode of said thermionic repeater, a connection between the control electrode of said second valve and said source of modulating potentials for impressing said modulating potentials on said second 15 valve to modulate said repeater, and a connection between said source of modulating potentials and the control electrode of said first thermionic valve to control the same in accordance with said modulating potentials to overcome the 20 normal bias applied to said repeater.
